WATER PUMP

Theodore H. Muhly, North Fork, Calif., assignor,
by decree of distribution, of one-third to Fred
Muhly, one-third to Clara Harris, and one-third
to Margaret Lewis

Application January 30, 1945, Serial No. 575,221

4 Claims. (Cl. 103—103)

1

This invention relates to a water pump of the centrifugal type; my major object being to provide a pump of this general character so constructed as to make effective use of the centrifugal force developed by the impeller as it rotates.

The impeller comprises a circular hollow body having a row of peripheral ports open to the rim of the body, and a suction intake in the bottom of said body. Since obviously the impeller body travels faster at its rim than elsewhere, the greatest centrifugal force or power will be developed at the rim thereof to produce the pumping or water lifting action.

Since the water as drawn into the impelled body from the intake leaves the body at said rim, I thus make full use of this great centrifugal force to lift the water.

I am therefore able to pump a relatively large amount of water with a pump unit of given size and power expenditure.

A further object of the invention is to produce a simple and inexpensive device and yet one which will be exceedingly effective for the purpose for which it is designed.

These objects are accomplished by means of such structure and relative arrangement of parts as will fully appear by a perusal of the following specification and claims.

In the drawings similar characters of reference indicate corresponding parts in the several views:

Figure 1 is a sectional elevation of my improved pump.

Figure 2 is a sectional plan on line 2—2 of Fig. 1.

Referring now more particularly to the characters of reference on the drawings, the pump comprises a cylindrical pump housing 1 disposed with its axis vertical and narrowing down at the top to form or join onto a vertical water outlet passage 2. The bottom of the housing is initially open, but is normally covered by a removable smooth-faced bottom plate 3 having a central water intake opening 4 and a tapped skirt 5 depending about the opening and to which a suction pipe 6 is connected.

The impeller, which is disposed in housing 1, comprises a cylindrical body 7 closed on top by a wall 7a which is connected to an axial upstanding drive shaft 8, journaled in a bushing 9 above the body and which is supported from a plate 10 extending over wall 7a for the full diameter of the body 7 in closely spaced relation to said wall. Plate 10 is secured to or formed with an upstanding dome 11 in and symmetrical to the adjacent

2

portion of the housing 1, to which it is secured by radial webs 12. The plate 10 prevents any water pressure from bearing down on the top of the impeller and which would consume power to no useful end. The body 7 is concentric with but of considerably smaller diameter than the surrounding portion of the housing. The body 7 includes a bottom plate 13 resting on and covering substantially the entire otherwise exposed area of housing plate 3. Plate 13 has a central opening 14 the same size as and matching opening 4.

The circumferential wall or rim of housing 1 is formed with a horizontal row of evenly spaced water outlet ports 15 thereabout; the combined area of all ports 15 being less than that of intake opening 14. Ports 15 are rectangular and are shorter vertically than the chamber 16 formed within body 7 and are disposed centrally of the height thereof; the internal wall of said chamber diverging from the top and bottom edges of the ports at the junction thereof with the outer periphery of the body as shown at 17 in Fig. 1.

The ports 15 in a horizontal direction, are formed by and between relatively thin radial vanes 18 extending the full distance between top wall 7a and bottom plate 13.

The impeller body is also formed with a cup 19 thereabout, which extends substantially to the wall of housing 1, and the bottom of which cup has an upward slope from the lower edge of the row of ports 15. This cup deflects the water upwardly with a minimum of resistance while its outer edge, traveling at high speed, forms a seal with the housing which together with the seal formed between plates 3 and 13, prevents any water from leaking down past the impeller.

In operation, by reason of the arrangement above set forth, rotation of the impeller at high speed sets up a tendency to vacuum therein, which causes water from the intake to flow into and fill the impeller. This water is then propelled through ports 15, and placed under pressure by reason of the converging form of the port walls and the relative size of the ports and intake. As soon as the water passes through said ports, it is at once acted on by the great centrifugal force exerted by the rim of the impeller and forced upwardly.

Since the impeller at its rim can thus throw or move more water than can enter the impeller chamber through the intake port, it is necessary to provide a relatively large intake port so as to maintain a steady pressure or flow at the outlet ports. The pressure and outlet volume obtained

can be varied by altering the relative sizes of the intake and outlet ports, as will be evident. Also, since the cup 19 is turning with the impeller, a centrifugal motion is imparted to the water in the pump chamber outside the impeller. This aids in the lifting of the water in the chamber.

In order to avoid possible air lock within the impeller, a bleed passage 20 is drilled through the top wall 1a of the impeller from the periphery thereof to a point well within the impeller.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. A pump comprising a cylindrical housing having a central intake opening in the bottom and a top outlet opening, a vertical axis impeller turnably mounted in the housing and being concentric therewith, such impeller including a hollow circular body, such body comprising a top and bottom plate, the inner surfaces of such plates curving respectively upwardly and downwardly from the side of the body toward the central vertical axis thereof, ports formed in the side of the body between the plates, the bottom plate having an orifice in register with the intake opening of the housing.

2. A structure as in claim 1 including a cup shaped member interposed between the body and the inner side wall of the housing, the curved inner face of such member forming a continu-

ation of the curved inner face of the bottom plate.

3. A structure as in claim 1 including a cup shaped member interposed between the body and the inner side wall of the housing, the curved inner face of such member forming a continuation of the curved inner face of the bottom plate, the top edge of said member lying in a horizontal plane above the horizontal plane of the ports.

4. A structure as in claim 1 including a cup shaped member interposed between the body and the inner side wall of the housing, the curved inner face of such member forming a continuation of the curved inner face of the bottom plate, the top edge of said member lying in a horizontal plane above the horizontal plane of the ports, and a plurality of relatively thin vertically disposed vanes projecting radially inward from the ports toward the central vertical axis of the body and extending between the top and bottom plates.
